(57) **CLAIM**

The ornamental design for a free-standing kiosk, as shown and described.

DESCRIPTION

FIG. 1 is a front right perspective view of the free-standing kiosk of the instant invention;

FIG. 2 is a front view thereof;

FIG. 3 is a rear view thereof;

FIG. 4 is a right side view thereof, the left side view being a mirror image thereof; and,

FIG. 5 is a top view thereof.

The broken lines illustrate unclaimed portions of the free-standing kiosk and form no part of the claimed design.

1 Claim, 5 Drawing Sheets

FIG. 1

FIG. 2

FIG. 3

FIG. 4

FIG. 5
